UNITED STATES PATENT OFFICE

JOHN L. BIXBY, OF ARLINGTON, MASSACHUSETTS, ASSIGNOR TO KE-BOND COMPANY, INCORPORATED, OF BOSTON, MASSACHUSETTS, A CORPORATION OF MASSACHUSETTS

METHOD OF FORMING CORRUGATED SHEETS

Application filed March 14, 1931. Serial No. 522,686.

This invention relates to a novel and improved method of forming bonding sheets, and will be understood by reference to the following description of the method, when taken in connection with the accompanying drawings illustrative thereof, while its scope will be pointed out more particularly in the appended claims.

In the drawings:

Fig. 1 is an edge elevation illustrating the appearance of the sheet in cross-section, following the first step of forming parallel corrugations having no overhanging surfaces, or "undercut";

Fig. 2 is an edge elevation of the sheet as in Fig. 1, but on an enlarged scale, and illustrating by dotted lines the step of applying forces to the sheet to convert the corrugations to their final form;

Fig. 3 is an edge elevation of the sheet in its final form, on the same scale as Fig. 1, illustrating by dotted lines the cross-sectional form shown in Fig. 1;

Fig. 4 is a cross-sectional view, illustrating portions of a pair of crimping or corrugating rolls, by which the first step in the method is performed; and

Fig. 5 is a cross-sectional view of portions of a pair of rolls, by which the second step in the method is performed.

Referring to the drawings, and to the method which is illustrated therein, and having reference at first to Fig. 3, which illustrates in full lines the sheet in its final form, there is shown a sheet of suitable material such as metal, usually steel, having two sets of oppositely-directed, dove-tail formations or corrugations, constituted by two sets of flat portions 10 and 11, whose faces are disposed in parallel planes A—A and B—B, and are connected by sets of portions 12 which are oblique to the portions 10 and 11. The sheet, as viewed from one side, is characterized by alternating ridges and grooves of dovetail formation, two adjacent ridges having sloping sides which overhang the intervening groove,—that is to say, considering the sides of each groove, they diverge from each other, from the plane A—A toward the plane B—B.

To those skilled in the art of rolling sheet metal, it must be evident that it is impracticable to form with a single pair of rolls a sheet of dovetail formation such as that illustrated in Fig. 3, because of the overhang

at the sides of each dovetail. Therefore, the first step is to form the sheet to present on each side grooves alternating with hollow ridges, which do not overhang the grooves. More specifically, this step comprises forming the sheet to present sets of parallel W-shaped formations 13, alternating with sets of parallel V-shaped formations 14. This step is conveniently accomplished by the use of a pair of rolls 15 (see Fig. 4), which are fluted lengthwise to correspond with the described formation illustrated in Fig. 1. The flat sheet is simply passed between the rolls, and comes through corrugated or crimped, with the formation imparted to it by the flutes on the rolls.

The second step is to flatten the center apexes 16 of the W-shaped formation into a common plane B—B, and to flatten the apexes 17 of the V-shaped formation into a common plane A—A, parallel with the plane B—B, and to turn the outer sides of the W-shaped formation about parallel central axes C (see Fig. 2), thereby to form the two sets of oppositely-directed, dovetail formations. This is accomplished by pressing on non-sequent apexes alternately from opposite sides of the sheet by simply exerting on each apex 16 a pressure in the direction of the arrow D, and to exert on each apex 17 a pressure in the direction of the arrow E. It follows that the acute angles F, shown in full lines in Fig. 2, become the more acute angles G, shown in dotted lines, as the faces 12 are turned about the central axes C.

This second step is accomplished conveniently by the use of a pair of forming rolls 18, longitudinally fluted to provide teeth 19 alternating with spaces 20 much wider than the teeth, the rolls being geared together and so placed with relation to each other that a tooth on one roll enters a space in the other, and occupies a position midway between two adjacent teeth of such other roll, as shown in Fig. 5. The sheet previously crimped or corrugated by the first step is passed between the rolls 18, in such a way that the tooth of one roll presses upon one apex 16, and the next adjacent tooth of the other roll then presses upon the next adjacent apex 17, and so on, the directions of the pressures being as previously described, shown by the arrows in Fig. 2. The completed sheet emerges from between the rolls

in its final form, illustrated in full lines in Fig. 3.

Having thus described the method, what I claim and desire by Letters Patent to secure is:—

1. The herein-described method of forming a corrugated sheet, which comprises advancing a sheet while corrugating the same transversely of the direction of the advance and keeping the following portion of the sheet without substantial restraint to present on each side grooves alternating with hollow ridges which do not overhang the grooves, and subsequently manipulating the ridges to provide them with sides which overhang the grooves.
2. The herein-described method of forming a corrugated sheet, which comprises advancing a sheet while corrugating the same transversely of the direction of the advance and keeping the following portion of the sheet without substantial restraint to present on each side grooves alternating with hollow ridges which do not overhang the grooves, and subsequently advancing the sheet transversely of the ridges and pressing on the ridges in succession to provide the ridges with sides which overhang the grooves.
3. The herein-described method of forming a corrugated sheet, which comprises advancing a sheet while corrugating the same transversely of the direction of the advance and keeping the following portion of the sheet without substantial restraint to present on each side grooves alternating with hollow ridges which do not overhang the grooves, and subsequently advancing the sheet transversely of the ridges and pressing on the ridges in succession to press each ridge toward the opposite side of the sheet to provide said ridges with sides which overhang the grooves.
4. The herein-described method of forming a dove-tail corrugated sheet, which comprises advancing a sheet while corrugating the same transversely of the direction of the advance and keeping the following portion of the sheet without substantial restraint to present non-reentrant serrations, and advancing the sheet transversely of the serrations and deforming the serrations in succession to present undercut serrations by pressure exerted on selected apexes.
5. The herein-described method of forming a corrugated sheet, which comprises advancing a sheet while corrugating the same transversely of the direction of the advance and keeping the following portion of the sheet without substantial restraint to present a zig-zag cross-section with ridges having sets of angularly disposed faces, and subsequently advancing the sheet transversely of said ridges and pressing on said ridges

in succession to cause certain pairs of angularly disposed faces to occupy a common plane, to cause other pairs of angularly disposed faces to occupy another common plane parallel with the first plane, and to cause other pairs of angularly disposed faces to form overhanging sides of dove-tail grooves alternating with dove-tail ridges.

6. The herein-described method of forming a dovetail corrugated sheet, which comprises advancing a sheet while corrugating the same transversely of the direction of the advance and keeping the following portion of the sheet without substantial restraint to present a serrated cross-section, and advancing the sheet transversely of the serrations while pressing successively on non-sequent apexes alternately from opposite sides of the sheet to flatten and evert the serrations corresponding to such apexes, and simultaneously to change the slope of a side intervening between said serrations.

7. The herein-described method of forming a dovetail corrugated sheet, which comprises advancing a sheet while corrugating the same transversely of the direction of the advance and keeping the following portion of the sheet without substantial restraint to present a serrated cross-section, and advancing the sheet transversely of the serrations while pressing successively on non-sequent apexes alternately from opposite sides of the sheet to flatten and evert the serrations corresponding to such apexes and evert them substantially to the original plane of the other apexes.

8. The herein-described method of forming a dovetail corrugated sheet, which comprises advancing a sheet while corrugating the same transversely of the direction of the advance and keeping the following portion of the sheet without substantial restraint to present sets of parallel W-shaped formations alternating with sets of parallel V-shaped formations, and subsequently advancing the sheet transversely of the formations while successively exerting on the center apex of each W-shaped formation and on the apex of each V-shaped formation pressures in opposite directions, respectively, and normal to said apexes, to flatten the center apexes of the W-shaped formations into a common plane, to flatten the apexes of the V-shaped formations into a common plane parallel with the first-mentioned plane, and to turn the outer sides of each W-shaped formation about parallel, central axes, thereby to form two sets of oppositely-directed, dovetail formations, the dovetail formations of one set alternating with the dovetail formations of the other set.

In testimony whereof, I have signed my name to this specification.

JOHN L. BIXBY.
